Davis

(57) **CLAIM**

The ornamental design for a sole for footwear, as shown and
described.

DESCRIPTION

Fig. 1.1 is a front elevation view of our new design for a sole
for footwear;

Fig. 1.2 is a rear elevation view thereof;

Fig. 1.3 is a left elevation view thereof;

Fig. 1.4 is a right elevation view thereof;

Fig. 1.5 is a top plan view thereof; and

Fig. 1.6 is a bottom plan view thereof.

(Continued)

The broken lines and surfaces they enclose represent unclaimed subject matter and form no part of the claimed design.

1 Claim, 6 Drawing Sheets
